UNITED STATES PATENT OFFICE.

CHARLES R. BURCH, OF COOPERSTOWN, NEW YORK.

DESIGN FOR A SPOON, &c.

SPECIFICATION forming part of Design No. 20,793, dated June 2, 1891.

Application filed April 23, 1891. Serial No. 390,175. Term of patent 3½ years.

To all whom it may concern:

Be it known that I, CHARLES R. BURCH, a citizen of the United States, residing at Cooperstown, in the county of Otsego and State of New York, have invented certain new and useful Improvements in Designs for Handles for Spoons, Knives, Forks, and other Culinary Tools; and I do declare the following to be a full, clear, and exact description of the invention, such as will enable others skilled in the art to which it appertains to make and use the same, reference being had to the accompanying drawing, and to the letters of reference marked thereon, which form a part of this specification.

This invention relates to certain new and useful improvements in designs for handles of spoons, knives, forks, and other culinary articles.

To this end the design consists in the features shown in the accompanying drawing, which forms a part of this specification, and to which reference may be had.

Reference being had to the drawing, it will be seen that the essential feature of the design consists of the representation of a man dressed in the prescribed outfit of a hunter as the same is shown in the "Leather Stocking Tales" of Fenimore Cooper. The man is

shown in an upright position. At his right hand is shown a dog. The hunter is shown as grasping in his hands the barrel of a gun, with its stock resting upon the base of the pedestal to the left of the figure, as shown. The pedestal forming the base of the figure is an enlargement of the shank of the handle of the spoon, and it is represented as supported upon an ornamental cap-piece resting upon the upper ends of two columns, which in turn are represented as resting at their lower ends upon an ornamental base at the end of the shank of the handle adjacent to the bowl of the spoon. Within the space intervening between the columns upon the face of the shank or handle appear the words "Leather Stocking."

Having thus described my invention, what I claim to be new, and desire to secure by Letters Patent, is—

The design for a handle for spoons, knives, and other like articles, substantially as herein shown and described.

In testimony whereof I affix my signature in presence of two witnesses.

CHARLES R. BURCH.
